UNITED STATES PATENT OFFICE.

FRANK C. RICHARDS, OF FELICITY, OHIO.

PERMUTATION-LOCK.

SPECIFICATION forming part of Letters Patent No. 530,551, dated December 11, 1894.

Application filed February 9, 1894. Serial No. 499,650. (No model.)

To all whom it may concern:

Be it known that I, FRANK C. RICHARDS, a citizen of the United States, and a resident of Felicity, Clermont county, State of Ohio, have 5 invented certain new and useful Improvements in Permutation-Locks; and my preferred manner of carrying out the invention is set forth in the following full, clear, and exact description, terminating with a claim 10 particularly specifying the novelty.

This invention relates to locks, and more especially to that class known as permutation; and the object of the same is to produce certain improvements in locks of this character.

To this end the invention consists in the specific construction hereinafter more fully described and claimed, and as illustrated in the accompanying drawings, wherein—

20 Figure 1 is an elevation of this lock with its face plate removed and the bolt withdrawn so that the device stands unlocked. Fig. 2 is an elevation of the lock with only the rear end of the face plate removed so as to show 25 the bolt as having been shot and two of the tumblers turned to prevent a retrograde movement. Fig. 3 is a perspective detail of the parts (slightly separated) of the tumbler which I preferably use. Fig. 4 is a vertical 30 section through the tumbler and the two sides of the casing.

Referring to the said drawings, the numeral 1 designates the rear plate and 2 the face plate of the casing, while 3 are the edge plates 35 thereof and 4 are the screws which may hold the parts together but are preferably employed to hold the lock on the door unless it is countersunk therein.

7 are screws preferably used to hold the 40 plates 1 and 2 together; and 5 is the bolt which is provided with longitudinal slots 6 sliding over the screws 7 so as to properly 45 guide it, and having (preferably near its rear end) a notch 8.

9 is a catch pivoted at 10 to the rear plate 1 and having a tongue or tip 11 working loosely in the notch 8, and the upper end of this catch has angular faces 12 borne upon by a spring 13 suitably connected with the 50 casing—the arrangement being such that the spring will bear on one of said faces when the bolt is in either of its extreme positions and

will ride over the angle between them during the movement of the bolt, the object being to hold the bolt frictionally in either of its two 55 positions as usual. At about the center of the bolt is formed a heart-shaped opening 14 surrounding a spindle 15 which receives the key whereby the bolt can be moved as usual, and the construction of this spindle is pref- 60 erably the same as those described below and indicated by the numeral 25. I have shown the bolt as also provided with four curved recesses 16, although it will be understood that there may be more or less of these re- 65 cesses which are to receive the tumblers.

The numeral 20 designates each tumbler which is shaped like a circular disk with a segment cut off on a true chord 21, and through the center of this disk is a hole 22 70 having a slot 23 projecting radially therefrom. Such of the tumblers as stand above the bolt are provided with rubber plugs 24 set into the body of the tumblers and projecting from one face thereof so as to frictionally contact with the inner surface of one of the plates 1 or 2—the object being to prevent the weight of the heavier side of the tumbler from turning it automatically and undesirably.

Through the hole 22 is loosely passed a spindle 25 having reduced extremities 26 which are journaled in corresponding openings 27 in the two plates 1 and 2; and said openings 27 have a number of radial slots 28 indicated on 85 the exterior of the lock by letters, figures, or scales 29. The slot 30 also extends longitudinally through the spindle and both its trunnions, completely bisecting each trunnion and extending from one side of the spindle en- 90

95 tirely through the body of the same to and excepting that portion thereof opposite, which stands in the curved line of the spindles. Such is the preferred construction of my tumblers; but at the lower side of Fig. 2 I have shown a tumbler 20' having an integral hub 26' which itself forms the trunnions and is provided with the slot 30' which is continued as at 23' out into the body of the tumbler. This is but a cheap way of constructing the tumblers though I consider it inferior to my preferred form for the reasons described below.

The key hole 40 may be provided with several radial slots 48, though on the drawings I

have shown but two. It will be understood that both face plates are provided with the holes or bearings 27 and 40 for the trunnions of the spindles, and both may be provided with 5 the radial slots and scales whereby the lock can be applied either face outward. These slots may be provided with teeth or may be struck on straight, curved, or broken lines, and the bit of the key correspondingly shaped 10 so that only the proper key can be used. In fact, the slots could be so arranged that one key would operate the bolt and another key the tumblers, or even so that entirely different keys must be used in all the holes. All parts 15 of the lock are of the desired sizes, shapes, materials, and proportions, and such changes may be made in the specific construction as come within the spirit of my invention. At this writing it occurs to me that coiled expansive springs might be substituted for the rubber plugs and that either might be inserted in the lowermost tumblers as well as in those above the bolt, as shown in the drawings; also that some other form of catch might be 20 employed in connection with the tumblers, or some other means for shooting the bolt.

In operation, the parts standing as shown in Fig. 1 and it being desired to shoot the bolt, the tip of the proper key is inserted in the 25 slot in the end of the key spindle 15 and the latter turned so that the bit of the key can be passed through one of the slots 48. The key is then pushed farther in and its bit passes into the heart-shaped opening 14, after which it is turned to shoot the bolt as usual and the 30 catch 9 moves to the position shown in Fig. 2. The key is then withdrawn through the opposite opening 48, and the tip of this key or another inserted in the slot 30 in the trunnion 35 26 of one of the spindles 25. The spindle is then turned to the proper slot 28 as indicated by the scale 29 so that the key can be pushed farther in and its bit will pass through this slot 28 and into the slot 23 in the tumbler. The key is then again turned so that 40 the tumbler is carried around, for instance, to one of the positions shown in Fig. 2, and as long as its body stands within the recess 16 in the bolt, the latter cannot be retracted. The key is then withdrawn through one of 45 the other slots 28 and the operator notes on the scale 29 which slot this is, and the spindle is then further turned so as to set its slot out of alignment with that in the tumbler, 50 after which the key is entirely removed. The other tumblers are then set in a similar manner so as to wholly or partially stand within the recesses 16 in the bolt.

To unlock this lock, each spindle must first 55 be turned with the tip of the key until its slot registers with that in the tumbler, which latter stands where it was left because of the friction of the plugs 24. The key is then pushed farther in and the tumbler turned 60 back to the point of starting where its chord 65 will stand adjacent the bolt as seen in Fig.

1, after which the key is removed and used on the other tumblers. When the latter have all been turned to the position shown in Fig. 1, the bolt is retracted and the lock is unlocked. 70

When the tumblers 20' are used, it will be obvious that the slot 30' in the spindle or hub 26' always registers with the slot 23' in the tumbler, and hence whenever this slot 30' 75 registers with one of those, 28, in the face plate of the lock, the key can be inserted and its bit will pass clear through into the tumbler. Therefore the simpler form above described is not so effective as the preferred 80 form; and furthermore, since the hub is integral with the tumbler, any tool which will turn the hub can be used to turn the tumbler, and therefore a lock of this character could be more easily picked than if the spindles 85 and tumblers were disconnected. With my preferred form of tumbler it will be necessary to unlock the lock to know with respect to each tumbler, first where to turn the spindle so as to cause its slot to register with that in 90 the tumbler, and then where to turn the tumbler so as to cause its chord to stand adjacent the bolt.

With a lock as illustrated and having four tumblers with five slots for each and independent spindles, this will give a great variety of combinations and will require that exactly the proper one be known in order to unlock the lock. 95

What is claimed as new is— 100

1. In a lock, the combination with a bolt having a number of recesses in its edge, and means for operating it; of a circular tumbler fitting each recess and having cut away a segment of the size of said recess, means for 105 turning the tumblers independently, and a rubber plug inserted in certain of the tumblers and bearing frictionally against the inner face of one of the face plates of the lock, as and for the purpose set forth. 110

2. In a lock, the combination with a bolt having a number of recesses in its edge, and means for operating it; of a circular tumbler fitting each recess and having cut away a segment of the size of said recess, a rubber 115 plug inserted in certain of the tumblers and bearing frictionally against the inner face of one of the face plates of the lock, and trunnions on each tumbler journaled in said face plates, the trunnion and tumbler being slotted 120 radially and one face plate being provided around the bearing for the trunnion with a number of radial slots marked with a scale, as and for the purpose set forth.

3. In a lock, the combination with a bolt 125 having a number of recesses in its edge, and means for operating it; of a circular tumbler fitting each recess and having cut away a segment of the size of said recess, and trunnions on each tumbler journaled in said face plates, 130 the trunnion and tumbler being slotted radially and both face plates being provided

around the bearing for the trunnion with a number of radial slots marked with a scale, as and for the purpose set forth.

4. In a lock, the combination with a bolt having a number of recesses in its edge, and means for operating it; of a circular tumbler fitting each recess and having cut away a segment of the size of said recess, the tumbler being provided with a central hole having a radial slot, and a spindle journaled in said hole and having reduced trunnions journaled in the face plates, the spindle and its trunnions having a radial slot and one face plate having a number of radial slots around the journal for the trunnion, as and for the purpose set forth.

5. In a lock, the combination with a bolt having a number of recesses in its edge, and means for operating it; of a circular tumbler fitting each recess and having cut away a segment of the size of said recess, a rubber plug inserted in certain of the tumblers and bearing frictionally against the inner face of one of the face plates of the lock, the tumbler being provided with a central hole having a radial slot, and a spindle journaled in said hole and having reduced trunnions journaled in the face plates, the spindle and its trunnions having a radial slot and both face plates having a number of radial slots around the journal for the trunnion, as and for the purpose set forth.

6. In a lock, the combination with a bolt sliding in suitable guides and having a heart-shaped opening, the edges of the bolt having

recesses, and a radially slotted spindle journaled between the face plates within said opening, one of said face plates being provided around said journal with a number of radial slots; of a number of tumblers having trunnions also journaled in the face plates, the trunnions and tumblers being radially slotted and the face plates around said journals being also provided with a number of radial slots, scales around said slots, the tumblers being circular so as to fit in said recesses in the bolt and having cut from one side a segment each of the size of its recess, and a catch for holding the bolt in one of two positions, as and for the purpose set forth.

7. In a lock, the combination with a bolt sliding in suitable guides and having recesses in its edges and a notch near its rear end, means for moving the bolt, and tumblers removably engaging said recesses; of a catch pivoted within the casing and having a tongue at one end engaging said notch and its other end provided with two flat faces standing at an angle with each other, and a spring bearing on one of said faces and adapted to ride over the angle when the bolt is moved, as and for the purpose set forth.

In testimony whereof I have hereunto subscribed my signature on this the 6th day of February, A. D. 1894.
